UNITED STATES PATENT OFFICE

107,811

DESIGN FOR A DRESS

Irene Welch, New York, N. Y.

Application October 19, 1937, Serial No. 72,302

Term of patent 3½ years

To all whom it may concern:

Be it known that I, Irene Welch, a citizen of the United States, residing in the county at Kings, city and State of New York, whose post office address is 3382 12th Avenue, Brooklyn, New York, have invented a new, original, and ornamental Design for a Dress, of which the following is a specification, reference being had to the accompanying drawing, constituting a part thereof.

Fig. 1 is a front view of the dress.

Fig. 2 is the rear view of the dress as shown in Fig. 1.

I claim:

The ornamental design for a dress, substantially as shown.

IRENE WELCH.
